UNITED STATES PATENT OFFICE.

STEVE RONDA, OF DETROIT, MICHIGAN.

THREAD AND TWINE CUTTING DEVICE.

1,073,522.

Specification of Letters Patent. Patented Sept. 16, 1913.

Application filed June 11, 1913. Serial No. 773,097.

To all whom it may concern:

Be it known that I, STEVE RONDA, a subject of the Emperor of Austria-Hungary, residing at Detroit, in the county of Wayne 5 and State of Michigan, have invented certain new and useful Improvements in Thread and Twine Cutting Devices, of which the following is a specification, reference being had therein to the accompanying 10 drawing.

This invention relates to a thread and twine cutting device, and the primary object of my invention is to provide a novel clamping device for holding a thread or twine 15 while the same is cut.

A further object of this invention is to provide a simple, durable and inexpensive device of the above type embodying corrugated clamping members that are locked together to hold a piece of thread or twine while the same is cut by a cutter carried by 20 one of said members.

With the above and other objects in view the invention resides in the novel construction, combination and arrangement of parts 25 to be hereinafter specifically described and then claimed.

Reference will now be had to the drawing, wherein:—

30 Figure 1 is a perspective view of the cutting device, Fig. 2 is a side elevation of the same, Fig. 3 is an end view of the device, and Fig. 4 is a plan of the device with one of the clamping members thereof removed.

35 A device in accordance with this invention comprises two clamping members, one of which is in the form of an oblong stationary block 1. The bottom of the block is transversely grooved, as at 2 for transverse strips 3 that are suitably secured to the block 1 and have the ends thereof apertured, as at 4 whereby said strips can be secured to a suitable support to prevent the block 1 from becoming accidentally displaced while the de- 40 vice is in use. The top of the block 1 is inclined and diagonally corrugated, as at 5, while the forward end of said block is beveled, as at 6.

50 Hinged to the rear end of the block 1 by a conventional form of hinge 7 is a clamping member 8, said member having the bottom face thereof diagonally corrugated, as at 9, the corrugations of said member corresponding to the corrugations 5 of the block 55 1, whereby a thread or twine can be clamped between the members.

Pivots connected, as at 10 to one side of the block 1 is an operating lever 11 that has a long flat arm 12 and a short curved arm 13, said curved arm extending under a strap 14 carried by the side of the member 8. The side of the block 1, adjacent to said lever is provided with a stop pin 15 that is engaged by said lever to limit the opening movement of the member 8. Connected to the same side of the block 1 by suitable fastening means 16 is a spring 17. One end 18 of the spring extends under the lever 11 and the opposite end 19 of said spring extends under a kickoff latch 20 pivotally connected, as at 21 to the forward end of the block 1. The same side of the block 1 is provided with a wear plate 22 having a keeper 23 to receive the long arm 12 of the lever 11. The spring 17 holds the clamping 75 member 8 normally open and when the long arm 12 of the lever is depressed the spring 17 is placed under tension. The long arm 12 of the lever 11 can be placed under the keeper 23 and when in such position the kickoff 80 latch 20 is depressed and the spring 17 is further under tension. It is with the member 8 closed upon a piece of thread or twine that the thread or twine is held while it is moved into engagement with a notched cutter, carried by the side of the member 8. After the thread or twine has been cut the kickoff latch 20 can be depressed to force the long arm 12 from under the keeper 23, at which time the tension of the spring 17 is 85 sufficient to elevate the long arm 12 and open the clamping member 8 relatively to the block 1, thereby permitting of the thread or twine being drawn or repositioned between the clamping members, whereby a desired 90 quantity of thread or twine can be measured and cut.

The clamping members can be made of light and durable wood and their appurtenances of metal.

One embodiment of the invention has been illustrated, but it is to be understood that the structural elements are susceptible to such variations and modifications as fall within the scope of the appended claims.

What I claim is:—

1. A thread and twine cutting device comprising a stationary clamping member and a hinged clamping member, said members having corrugated confronting faces adapted to hold a thread or twine, a notched cutter carried by said hinged clamping member.

ber, a spring pressed lever carried by said stationary member for moving said hinged member, and means carried by said stationary member for holding said lever with said hinged member in a closed position.

2. A thread and twine cutting device comprising a stationary clamping member and a hinged clamping member, said members having corrugated confronting faces adapted to hold a thread or twine, a notched cutter carried by said hinged clamping member, a spring pressed lever carried by said stationary member for moving said hinged

member, means carried by said stationary member for holding said lever with said hinged member in a closed position, and means carried by said stationary member for releasing said lever whereby said hinged member can assume an open position.

In testimony whereof I affix my signature 20 in the presence of two witnesses.

STEVE RONDA.
